UNITED STATES PATENT OFFICE.

LEA HOFFMAN SANDS, OF SANTA MONICA, CALIFORNIA.

APPENDAGE GARMENT.

1,187,556.

Specification of Letters Patent. Patented June 20, 1916.

Application filed March 1, 1916. Serial No. 81,441.

To all whom it may concern:

Be it known that I, LEA HOFFMAN SANDS, a citizen of the United States, residing at Santa Monica, in the county of Los Angeles 5 and State of California, have invented new and useful Improvements in Appendage Garments, of which the following is a specification.

My invention relates to the support and 10 adjustment of a woman's napkin for use in the usual way, and has for its object the provision of a combined under shirt and napkin supporter for women which shall be comfortable in every respect to the 15 wearer; which shall contain no stiff material; in which the appendage shall be free, beginning at a point above the waist line, thus leaving the shirt free below this point; in which the position of the elastic appendage strip upon the shirt, combined with the 20 elasticity of the garment itself, produces a maximum of comfort; and in which the napkin attachment to and removal from the appendage is greatly facilitated.

25 The invention consists in the novel construction and combination of parts herein-after described and claimed, and illustrated in perspective in the accompanying drawing, portions being broken away to show 30 the details of construction.

Referring to the drawing, A represents the undershirt or garment which is made of "ribbed" or other form fitting or elastic material. Inside the shirt A are located 35 strips B and B', which are preferably similar in construction and similarly located and attached to the shirt, one in the front and the other in the back thereof, so that the description of one will suffice for both. 40 Strip B is made of flexible elastic material, such as cotton fabric having these qualities, and is suitably attached to the shirt, as by being woven thereto. It is centrally located and is attached from a point b near the 45 neck to a point b¹ immediately above the waist line, from which latter point downward it is unattached and extends to constitute an appendage b² for the attachment of a napkin. Toward the lower end of 50 appendage b² I provide one or more eyelets, b³ preferably of non-corrodible metal or other material for the ready attachment of the napkin by means of safety pins c or other fasteners. This is of great advantage 55 for two reasons, first, because such pins or

fasteners would otherwise tear the fabric of the appendage or tab, and second, because when the tab is wet or even moist, it is difficult to insert the pin.

A combined garment and napkin supporter constructed as above described, has many advantages. The strips are, by reason of their position, elastically supported by the garment, and are themselves elastic, thus permitting the utmost freedom of 60 movement of the body. If they were made of inelastic material and otherwise disposed, as, for instance, extending over the shoulders and diagonally across the back and breast, they would seriously interfere with 65 the movements of the body and produce great discomfort. By employing elastic strips, furthermore, the elasticity of the shirt and of the strips simultaneously is utilized for the support, and a maximum of 70 efficiency and comfort results.

The arrangement of weaving the strips into the garment itself does not detract from the garment as an undershirt, and the elasticity of both garment and the strips 75 acts more perfectly.

By having the appendage or tab unattached from a point above the waist line downward, the entire shirt is left free for drapery below the waist and at the same 80 time another garment may be adjusted around the waist under the shirt, as is frequently desired, without interfering with the napkin support.

Having described my invention, what I 90 claim as new, and desire to secure by Letters Patent of the United States, is:

A garment of the class described comprising an undershirt of elastic material, an integral strip of elastic material centrally 95 located inside the front of said shirt and woven into the material thereof from a point adjacent the neck to a point adjacent the waist line, said strip extending thence unattached and provided with means for 100 the attachment of a napkin, and a similar strip located in like manner in the back of said shirt.

In testimony whereof I affix my signature in presence of two witnesses.

LEA HOFFMAN SANDS.
